UNITED STATES PATENT OFFICE.

ARTHUR J. MOXHAM, OF JOHNSTOWN, PENNSYLVANIA.

RAILROAD-RAIL CHAIR.

SPECIFICATION forming part of Letters Patent No. 355,779, dated January 11, 1887.

Application filed April 14, 1886. Serial No. 198,786. (No model.)

To all whom it may concern:

Be it known that I, ARTHUR J. MOXHAM, of Johnstown, in the county of Cambria and State of Pennsylvania, have invented a new 5 and useful Improvement in Railroad-Rail Chairs, which invention or improvement is fully set forth and illustrated in the following specification and accompanying drawings.

The object of this invention is to make a 10 chair of wrought metal which shall be capable of tightly fitting into and clamping the webs of rails provided with stubs or beaded edges at the bottom of said webs.

The invention consists of the article of manufacture as hereinafter described, and set forth 15 in the claim.

Figure 1 shows a wrought-iron chair in perspective. Fig. 2 shows a wrought-iron chair, also in perspective, but having its standards 20 formed all in one piece with the rest of the chair, instead of in separate pieces, as shown in Fig. 1.

In said figures the several parts are indicated by letters, as follows:

25 The letter E indicates a plate having as part thereof the two standards A A diagonally placed and of such form that the upper parts a a of said standards bear with a neat fit against shoulders upon either side of the web of the 30 rail. (Not shown.) The spike-holes F F are placed diagonally, two only being shown; but more may be added, if deemed advisable.

The standards A A in Fig. 1 may be either drop-forged or rolled to the required shape, 35 and are secured to the base-plate E by rivets b b.

Fig. 2 shows a wrought-metal chair, also of shape like that shown in Fig. 1; but the standards A A in this case are stamped out of the metal E, the spaces left by such stamping being 40 indicated by the letters H H. Said standards, having been thus stamped or punched out, are then drop-forged to shape. This is the preferable mode of manufacture, Fig. 1 showing only a modification.

45 In each of the variations of structure above shown the principle of operation and location of the standards A A are the same. Said standards are diagonally located, and are each offset, as shown, to neatly fit over the stub or 50 fillet of the web of the rail. Such location of said standards, by providing a sufficient dis-

tance between them, permits the lower stub, G, of the rail to enter said chairs between their two standards A A. Their distance apart in a straight transverse line is such that when 55 said standards are brought to a true plane with the rail the parts a a fit snugly and neatly into the rail under its shoulders on either side of its web, and also make a similar fit over or upon the stub or lower fillet of said web. 60

When the track is being laid, the chairs are slipped diagonally into place over the rails, and the spikes, which, diagonally placed, secure the chairs in track, are then driven in and hold them true to a fit to the rails, as be- 65 fore described. The chairs thus held, the subsequent bonding of the road-bed material or ballast around them serves to further secure said chairs in place.

The considerable advantage of this form of 70 chair lies in the fact that great facility is afforded for placing such chairs at any point in the length of the rail. Where chairs are used which are bolted through the webs of the rails in securing the rail and chair together, al- 75 though the necessary holes are drilled at the works or shops previous to shipment, yet such method of fitting necessitates the adoption of exact points where only the chairs, and, con-sequently, the cross-ties, can be placed when 80 the construction of the track is progressing. In constructing the track it is found to add considerably to the cost to be compelled to exactly locate the cross-ties for the chairs, as in the case above mentioned must be done. 85 The excavations for the cross-ties being gen-erally made by ordinary day laborers, such unskilled labor, if compelled to work to much exactness, is usually slow and uncertain and loses much time in making mistakes. Exact- 90 ness of location of cross-ties, therefore, if de-manded, becomes an item of considerable cost. The best method, therefore, is one in which slight variations of cross-tie spaces are per-missible, and such variation and adjustment 95 of distances is rendered quite feasible and facile by the form and construction of chair herein-above described as the subject of this inven-tion. The time and cost of securing the bolts and nuts in the usual construction of chairs 100 provided with standards is also saved, which is quite an item in saving, as there are from

seventeen hundred to two thousand chairs attached to the rails for every mile of track.

I am aware that diagonal lugs for clamping the edges of the lower or base flanges of rails 5 have heretofore been used, and such I do not claim; but,

Having thus fully described my said rail-chairs, as of my invention I claim—

As a new article of manufacture, a railroad-10 rail chair of wrought metal struck up and drop-forged to shape, substantially as described, pro-

vided with diagonally-placed standards offset to clamp the web of the rail over the stub or beaded foot of said web, and, while free to be entered diagonally on such rail, fits into and 15 ties the same when spiked down true thereto in the track, substantially as and for the purposes set forth.

ARTHUR J. MOXHAM.
